United States Patent Office

Des. 186,945
Patented Dec. 29, 1959

186,945

BATTERY CHARGER

Eston H. Smith, Indianapolis, Ind., assignor to Rex Metal-Craft, Inc., Indianapolis, Ind., a corporation

Application January 20, 1959, Serial No. 54,245

Term of patent 3½ years

(Cl. D26—15)

FIG. 1

FIG. 2

FIG. 3

Fig. 1 is a front elevational view of a battery charger, showing my new design, the rear being conventional;

Fig. 2 is a side elevational view, the opposite side being substantially a mirror image thereof; and

Fig. 3 is a top plan view, the bottom being substantially a mirror image thereof.

I claim:

The ornamental design for a battery charger, as shown and described.
